UNITED STATES PATENT OFFICE

2,442,999

HYDRAULIC CLUTCH OF THE TRANS-
VERSELY MOBILE PISTON TYPEJames F. Ekleberry, Miami, Fla., assignor of one-
half to C. Roy Miller, Miami, Fla.

Application November 10, 1945, Serial No. 627,869

6 Claims. (Cl. 192—60)

1

This invention relates to a fluid drive, and more particularly to a fluid clutch connection between a drive member and a driven member.

A primary object of this invention is the provision of an improved fluid drive mechanism whereby a drive shaft may impart power to a driven shaft with a maximum of efficiency, and a minimum of lost power.

A further object of the invention is the provision of such a connection characterized by a fluid filled, fluid tight housing containing a movable casing and a rotatable drum having a plurality of reciprocable pistons therein, the pistons being driven by an eccentric in such manner as to circulate the fluid, in accordance with the position of the casing with relation to the drum to impart through the fluid the power of the drive shaft to the driven shaft in accordance with the relative positions of the internal elements thereof.

An additional object of the invention is the provision of an improved control means for such a device, characterized by means whereby the fluid circulation between the two housings may be increased or retarded in accordance with the degree of power it is desired to impart to the driven shaft, in respect to the power provided by the drive shaft.

Still another object of this invention is the provision of such a device characterized by a relative minimum of working parts, whereby extreme smoothness of drive is obtained, which is sturdy and durable in construction, reliable and efficient in operation, and relatively simple and inexpensive to manufacture and assemble.

Other objects will in part be obvious and in part be pointed out as the description of the invention proceeds and shown in the accompanying drawings wherein there is disclosed a preferred embodiment of this inventive concept.

In the drawings;

Figure 1 is a side or edge elevational view of one form of device embodying features of the instant invention.

Figure 2 is a front or face elevational view of the device shown in Figure 1.

Figure 3 is a sectional view taken substantially along the line 3—3 of Figure 2 as viewed in the direction indicated by the arrows.

Figure 4 is a sectional view taken substantially along the line 4—4 of Figure 1 as viewed in the direction indicated by the arrows.

Figure 5 is a sectional view taken through the casing showing certain interior parts thereof in elevation.

Figure 6 is a fragmentary sectional view taken

2

through the casing and the interior mechanism thereof substantially on the line 6—6 of Figure 5.

Figure 7 is a view similar to Figure 5 but showing the parts in a different position of adjustment.

Figure 8 is a sectional view taken substantially along the line 8—8 of Figure 7.

Figure 9 is a view similar to Figures 5 and 7 but showing the parts in a still different position of adjustment.

Figure 10 is a sectional view taken substantially along the line 10—10 of Figure 9.

Figure 11 is a fragmentary detail sectional view taken substantially along the line 11—11 of Figure 4.

Similar reference characters refer to similar parts throughout the several views of the drawings.

The fluid drive or clutch of the instant invention comprises a cylindrical casing 20, to which are secured as by means of a plurality of screws 21 and 22, respectively, side plates 23 and 24. The side plate 23 is provided with a centrally disposed aperture having a bushing 25 therein to which is secured as by screws 26 a sealing ring 27 compressing therein a sealing gasket 28 against the sides of a drive shaft 29. The drive shaft 29 terminates in a stub shaft 30, journaled in a recess 31 in a driven shaft 32, which enters 30 through a suitable bushing 33 in side plate 24, through a sealing ring 35 secured to bushing 33 as by a series of screws 36, and compressing a sealing gasket or ring 37.

Thus it will be seen that the drive shaft and the driven shaft terminate in fluid tight sealed relation within the housing formed by the casing 20 and the end plates 23 and 24.

The driven shaft 32 terminates interiorly of the housing 20 in a drum 40 provided with a plurality of radial bores 41 therethrough. The bores 31 are substantially identical in configuration, and are formed in two rows, in alignment that is in such a manner that the radial bores of the first

45 are spaced parallel to the radial bores of the second row. Each of the bores 41 contains a piston 42, terminating at its inner extremity as best shown in Figure 11 in a bifurcated portion comprised of bifurcations 43 between which is mounted a guide roller 44 as on a pin 45. Each guide roller is surrounded by a band 46. The guide

50 rollers are cut away to form an interior channel 47 between the bifurcations 43, which channel accommodates a rotatable guide ring 48, which guide ring is positioned for rotation in a central cavity in the drum 40.

The drive shaft 29 is provided with two oppositely disposed eccentrics 50, each in alignment with one of the rings 48 in the central bore of the drum 40, the arrangement being such that the eccentric abuts at all times the rollers 44 of each of the pistons 42 in both of the radial groups thereof.

Thus it will be seen that rotation of the driven shaft 29 causes alternate radial reciprocation of the series of pistons 42, in sequential relation, one row being forced outwardly, while the adjacent piston thereof in the associated row is in its innermost position.

Surrounding the drum 40 in slidable relation therewith is a sleeve 51, provided with a plurality of radial ports 52 so aligned that when the sleeve is in one position of adjustment, as best shown in Figure 5 the ports 52 will align with the openings of the bores 41.

As best shown in Figures 5, 7 and 9, the sleeve 51 is connected with the drum 40 as by means of a plurality of inclined slots 53 in the sleeve within which are engaged pins 54 carried by the drum 40.

Thus it will be seen that linear movement of the sleeve 51 with respect to drum 40 is translated simultaneously into rotative angularly displaced movement with respect thereto.

Means are provided for accomplishing such linear radial movement, and takes the form of a series of peripheral channels 55 about the exterior of sleeve 51, which are engaged by oppositely disposed gears 56, mounted on shafts 57, which shafts 57 extend exteriorly of oppositely positioned flanges 58 mounted on the sides of the housing 20. From the foregoing it will now be seen that simultaneous rotation of the shafts 57, which may be effected in any desired conventional manner will serve to move the drum 51 linearly within the housing 20, and hence linearly with respect to the drum 40, but that such linear movement with respect to the drum 40 will be translated into radial movement by virtue of the pin and slot connection previously described.

The housing 20 is fluid filled with any suitable hydraulic fluid, and it will be seen that when the parts are in the position disclosed in Figures 5 and 6 with the ports 52 aligned with each of the bores 41 that the pressure exerted on the fluid therewithin by the pistons 42 will pass radially through the ports into the housing and be relatively freely circulated therewithin. Under such conditions it will be apparent that the rotation of the drive shaft 29 will have substantially no effect on the driven shaft 32, and that the drive will be in substantially neutral position. However, when the ports are partially closed as shown in Figures 7 and 8, a certain amount of torque will inevitably be imparted by the rotation of the shaft 29 to the driven shaft 32 and in accordance with the relative opening left by the position of the ports 52 as effected by the sleeve 51, the driven shaft will rotate at a speed relative to the speed of the driven shaft in accordance with the relative opening left between the ports 52 and the bores 41. Correspondingly, when the ports are moved to fully closed position as shown in Figures 9 and 10 and the full impact of the fluid as driven by the pistons 42 is imparted to the drum 40, it will be understood that a full fluid drive will be effected and that the driven shaft 32 will rotate at a speed, and with a smoothness, substantially equivalent to that of the drive shaft.

Thus it will be seen that there is herein pro-

vided an improved fluid drive mechanism where-
in the relative speed of drive and driven shafts
may be regulated with a maximum of efficiency,
and with a minimum of lost power or motion
between such members, and whereby an effec-
tive clutch may be realized without the necessity
of shifting gears, or similar common expedients.

From the foregoing it will now be seen that
there is herein provided an improved fluid drive
accomplishing all of the objects of this inven-
tion, and others, including many advantages of
great practical utility and commercial im-
portance.

As many embodiments may be made of this
inventive concept, and as many modifications
may be made in the embodiment hereinbefore
shown and described, it is to be understood that
all matter herein is to be interpreted merely
as illustrative and not in a limiting sense.

I claim:

1. In a fluid drive; in combination, a fluid filled housing, a drive shaft having an eccentric thereon in said housing, a driven shaft having a drum thereon in said housing, said drum having a central aperture into which said eccentric extends, and a plurality of radial bores therethrough, pistons in said bores reciprocable by said eccentric, and means for opening and closing said bores, said last mentioned means including a sleeve having apertures therein normally coincident with the exterior mouths of said bores, slidable and rotatable on said drum, said sleeve having a pin and slot connection with said drum to effect rotative movement thereof when moved axially of said sleeve.

2. In a fluid drive; in combination, a fluid filled housing, a drive shaft having an eccentric thereon in said housing, a driven shaft having a drum thereon in said housing, said drum having a central aperture into which said eccentric extends, and a plurality of radial bores therethrough, pistons in said bores reciprocable by said eccentric, means for opening and closing said bores, said last mentioned means including a sleeve having apertures therein normally coincident with the exterior mouths of said bores slidable and rotatable on said drum, said sleeve having a pin and slot connection with said drum to effect rotative movement thereof when moved axially of said sleeve, and means for moving said sleeve from the exterior of said housing.

3. In a fluid drive, in combination, a fluid filled housing, a drive shaft having an eccentric thereon in said housing, a driven shaft having a drum thereon in said housing, said drum having a central aperture into which said eccentric extends, and a plurality of radial bores therethrough, pistons in said bore reciprocable by said eccentric, means for opening and closing said bores, said last mentioned means including a sleeve having apertures therein normally coincident with the exterior mouths of said bores slidable and rotatable on said drum, said sleeve having a pin and slot connection with said drum to effect rotative movement thereof when moved axially of said sleeve, and means for moving said sleeve from the exterior of said housing, said last mentioned means including peripheral teeth on said sleeve, gears coacting with said teeth, and shafts connected to said gears extending out of said drum.

4. In a fluid drive, in combination, a fluid filled housing, a drive shaft having an eccentric thereon in said housing, a driven shaft having a drum thereon in said housing, said drum having

a central aperture into which said eccentric extends and a plurality of radial bores therethrough, pistons in said bores reciprocable by said eccentric, each of said pistons having a bifurcated inner extremity, a roller journalled between said bifurcations, but positioned to leave a space therebetween outwardly of said rollers, said rollers contacting said eccentric, and an annular ring extending through all of said spaces about said central aperture, and means for varying the extent of the outer opening of said bores through said drum, said last mentioned means including a sleeve having apertures therein normally coincident with the exterior mouths of said bores axially slideable and rotatable on said drum, said sleeve having a pin and slot connection, said pin being affixed to said drum, and said slot being helically disposed in said sleeve, to effect rotative movement of said sleeve with respect to said drum when moved axially of said drum.

5. In a fluid drive, in combination, a fluid filled housing, a drive shaft having an eccentric thereon in said housing, a driven shaft having a drum thereon in said housing, said drum having a central aperture into which said eccentric extends and a plurality of radial bores therethrough, pistons in said bores reciprocable by said eccentric, each of said pistons having a bifurcated inner extremity, a roller journalled between said bifurcations, but positioned to leave a space therebetween outwardly of said rollers, said rollers contacting said eccentric, and an annular ring extending through all of said spaces about said central aperture, and means for varying the extent of the outer opening of said bores through said drum, said last mentioned means including a sleeve having apertures therein normally coincident with the exterior mouths of said bores axially slideable and rotatable on said drum, said sleeve having a pin and slot connection, said pin being affixed to said drum, and said slot being helically disposed in said sleeve, to effect rotative movement of said sleeve with respect to said drum when moved axially of said drum, and means for moving said sleeve from the exterior of said housing.

6. In a fluid drive, in combination, a fluid filled housing, a drive shaft having an eccentric thereon in said housing, a driven shaft having a drum thereon in said housing, said drum having a central aperture into which said eccentric extends and a plurality of radial bores therethrough, pistons in said bores reciprocable by said eccentric, each of said pistons having a bifurcated inner extremity, a roller journalled between said bifurcations, but positioned to leave a space therebetween outwardly of said rollers, said rollers contacting said eccentric, and an annular ring extending through all of said spaces about said central aperture, and means for varying the extent of the outer opening of said bores through said drum, said last mentioned means including a sleeve having apertures therein normally coincident with the exterior mouths of said bores axially slideable and rotatable on said drum, said sleeve having a pin and slot connection, said pin being affixed to said drum, and said slot being helically disposed in said sleeve, to effect rotative movement of said sleeve with respect to said drum when moved axially of said drum, and means for moving said sleeve from the exterior of said housing, said last mentioned means including peripheral teeth on said drum, gears co-acting with said teeth and shafts connected to said gears extending exteriorly of said drum.
